DESIGN FOR A DOLL OR THE LIKE

Lydia Mead, New York, N. Y.

Application April 12, 1941, Serial No. 100,353

Term of patent 3½ years

To all whom it may concern:

Be it known that I, Lydia Mead, a citizen of the United States, residing at New York, in the county of New York and State of New York, have invented a new, original, and ornamental Design for a Doll or the like, of which the following is a specification, reference being had to the accompanying drawing, forming part thereof wherein:

I claim:

The ornamental design for a doll or the like, substantially as shown.

LYDIA MEAD.
